UNITED STATES PATENT OFFICE.

FRANK A. BOND, OF PITTSBURGH, PENNSYLVANIA.

CROSS-CHAIN EMERGENCY REPAIR LINK.

1,411,836.

Specification of Letters Patent.

Patented Apr. 4, 1922.

Application filed September 7, 1921. Serial No. 498,985.

To all whom it may concern:

Be it known that I, FRANK A. BOND, a citizen of the United States, residing at Pittsburgh, in the county of Allegheny and State 5 of Pennsylvania, have invented certain new and useful Improvements in Cross - Chain Emergency Repair Links; and I do hereby declare the following to be a full, clear, and exact description of the same, reference being had, to the accompanying drawings, forming part of this specification.

This invention relates to links intended for repair use of broken cross or tread chains on tire grips or anti-skid chains, and has for its 15 object the provision of a simple and efficient link that may be merely hooked to the opposite ends of the broken chain, with the assurance that the link will remain in place without the necessity of having to crush down 20 the return bends of the link.

There are at present a number of repair links on the market, but practically all of these are either inefficient or are too complicated for general use. The other types are 25 of simpler manufacture but they require that the user bend down the free ends of the link in order to make a satisfactory emergency connection. In the present link no closing down of the ends is required and after a considerable use it has been found that these 30 links positively eliminate the possibility of the link becoming disengaged, the centrifugal force of the chain when the car is in motion positively holding the link in its 35 proper position.

In the drawings,—

Figure 1 represents a side view of the link.

Figure 2 is a central vertical cross section. 40 The link is formed of an integral piece of round rod, bent to form a back or intermediate portion 10, and return bends consisting of the side members 11 and the ends 12. The faces 14 of the ends are, for convenience of manufacture, sheared at right angles to the axis of the rod and hence appear as circular faces, and these are spaced apart substantially the diameter of the links to be connected.

50 An important feature of the present invention lies in the provision of a hump 15 formed in the mid-portion of the back, the rod being bent inward toward the two opposed faces 14, so that the distance from the crest 16 of the hump to the nearest point 17 of either of the faces is the same as the dis-

tance between the points 17. The two points 17 and the crest point 16 therefore form the vertices of an equilateral triangle indicated in the drawing by the dotted line 18.

The sides 11 of the link converge as they turn from the back or intermediate portion of the link, and therefore make an acute angle with a line passing through from the lowest point 19 on either side of the inward 65 bend of the back. The end portions 12 are of approximately the same length as the sides, and make approximately a right angle with these sides, so that the two ends 12 are deflected inward toward the hump of the 70 back.

In using this repair link the idea is merely to hook the opposite ends of the broken chain in each end of the repair link, and in view of the hump portion in the back 75 there is no need to close down the ends of the link. It is, therefore, easy to remove the repair link when the chains are taken from the tire to replace the emergency link with a welded one.

80 What is claimed is:

1. A repair link consisting of a rod of uniform diameter throughout its entire length bent to form a back and two return portions, the latter each having opposed faces spaced 85 apart to permit the passing between them of the links to be connected, characterized by the provision of an inwardly directed hump in the mid-portion of said back.

2. A repair link consisting of a rod of uniform diameter throughout its length bent to form a back having an inwardly directed humped portion, converging side members, each forming an acute angle with said back and ends at substantially a right angle to 95 said sides, whereby said ends are deflected inwardly toward said humped portion.

3. A repair link consisting of a rod of uniform diameter throughout its length bent to form a back having an inwardly directed 100 humped portion, converging side members each forming an acute angle with said back and ends at substantially a right angle to said sides whereby said ends are deflected inwardly toward said humped portion, said 105 ends having opposed faces spaced from one another substantially the diameter of the links to be connected.

4. A repair link consisting of a rod of uniform diameter throughout its length bent to 110 form a back having an inwardly directed humped portion, converging side members

each forming an acute angle with said back and ends at substantially a right angle to said sides whereby said ends are deflected inwardly toward said humped portion, said ends having opposed faces spaced apart a distance substantially equal to the distance from the crest of said humped portion to the nearest point in either head.

5. A chain link having an intermediate portion and a pair of return portions ending 10 in spaced opposed faces, characterized by the provision of a hump in said intermediate portion, the crest of said hump and the inner tips of said faces forming the vertices of an equilateral triangle.

FRANK A. BOND.
